UNITED STATES PATENT OFFICE.

CLARENCE A. FOGELSTROM AND EMIL J. KUHN, OF JUNCTION CITY, KANSAS; SAID
KUHN ASSIGNOR TO SAID FOGELSTROM.

BOOTJACK.

1,210,295.

Specification of Letters Patent. Patented Dec. 26, 1916.

Application filed June 9, 1916. Serial No. 102,786.

To all whom it may concern:

Be it known that we, CLARENCE A. FOGELSTROM and EMIL J. KUHN, citizens of the United States, residing at Junction City, in the county of Geary and State of Kansas, have invented new and useful Improvements in Bootjacks, of which the following is a specification.

This invention relates to boot jacks and the principal object of the invention is to provide a simple and efficient device of this character whereby the jaws may be adjusted so as to fit various sizes of heels from the smallest to the largest boot.

Another object of the invention is the provision of novel means for effectively holding down the toe of the boot while the heel is being lifted which means is adjustable to provide for different lengths of boots.

Another object of the invention is the provision of simple and efficient means for operating the members to reduce or increase the size of the space between the jaws which are movable positively in either direction.

Further objects of the invention will appear as the following specific description is read in connection with the accompanying drawings which form a part of this application, and in which:

Figure 1 is a top plan view. Fig. 2 is a bottom plan view. Fig. 3 is a side elevation. Fig. 4 is a detail transverse sectional view on the line 4—4 of Fig. 2. Fig. 5 is a transverse sectional view on the line 5—5 of Fig. 1.

Referring more particularly to the drawing, the jack comprises a supporting cleat or batten 1 upon which is mounted the separate members 2 and 3 each of which are similarly formed at their outer ends to provide a U-shaped recess or socket 4. The edges of the members around the socket are preferably covered with a continuous strip of some suitable frictional material such as pigskin or the like as shown at 5 in order that a firm grip of the jaws may be obtained upon the boot heel and also in order to eliminate scratching of the heel. The members 1 and 2 are connected together by a link 6 having bolts extending downwardly

loosely through opposite ends of the link, through the members 2 and 3 and threaded into the cleat or batten 1. In order to prevent any relative displacement longitudinally the member 3 is provided with suitable sockets 7 which are engaged by pins 8 carried upon the member 2.

Secured to the under side of the members 2 and 3 are separated lugs 9 and 10 in which is threaded a right and left-hand screw 11 having a knurled head 12 arranged intermediate its ends so as to facilitate the operation thereof. By rotating the screw in the proper direction, the jaws may be contracted or expanded as desired to provide for large or small boots as will be readily understood.

Secured to the under side of each member are a pair of eyes 13 in which is slidably mounted the legs of a substantially U-shaped spring member 14 whose outer end is upwardly turned and covered with a protective covering 15 in the form of a rubber tube or similar device. The spring member 14 is adjustable in the eyes longitudinally of the members.

As shown, the members are preferably covered with some suitable frictional material such as corrugated rubber sheeting so that the operator may get a firm foothold upon the jack to prevent the same from slipping while removing the boot.

What is claimed is:

1. A boot jack comprising a supporting cleat, a pair of members pivotally mounted upon the cleat intermediate their ends, each member being cut away at one end whereby the cut away portions of said members will form a U-shaped recess, a continuous strip secured to the edge of said recess, one of said members being formed with socket in its inner edge, pins fixed in the other member at its inner edge and engaged in said socket, a U-shaped spring having its limbs carried by said member, and means for adjusting the members toward and away from each other.

2. A boot jack comprising a cleat, a pair of members pivoted to the cleat, a link connected to the pivot for the members, means on one member and engaged in the other

member for preventing relative longitudinal movement of said members, said members being cut to form a recess therebetween, means for adjusting the members relative to each other, and a U-shaped spring having its limbs fixed to the members and coacting with the cut away portions of said members.

Copies of this patent may be obtained for five cents each, by addressing the "Commissioner of Patents, Washington, D. C."

In testimony whereof we affix our signatures in presence of two witnesses.

CLARENCE A. FOGELSTROM.

EMIL J. KUHN.
